PICTURE REPRODUCING SYSTEM

Fritz Schröter, Berlin, Germany, assignor to Tele-funken Gesellschaft fur Drahtlose Telegraphie m. b. H., Berlin, Germany, a corporation of Germany

Application March 23, 1932, Serial No. 600,698
In Germany March 14, 1931

2 Claims. (Cl. 178—6)

As an auxiliary means in the amplification of picture-point currents in picture telegraphy and in television, there is mostly used an auxiliary carrier wave of a frequency being higher than the highest picture impulse frequency to be amplified. This auxiliary carrier wave is supplied at the lowest possible point of the amplifier arrangement, say, by the periodic interruption of the light ray pencil scanning the picture to be transmitted by the aid of a revolving perforated wheel. At the receiving end the said carrier frequency can be eliminated again by the aid of rectification in conjunction with selective means in order that the means serving for the re-creation of the picture (electrochemical recording device, glow-discharge lamp, Kerr cell, string galvanometer, etc.) will be acted upon only by the picture signals. However, in many instances elimination of the carrier frequency at the receiver end is dispensed with in order that the device recording or re-creating the picture may be adaptable to the end or power stage of the amplifier; in fact, some picture re-creators such as a gaseous-conduction lamp with external electrodes, as a matter of principle, are operable only by the aid of modulated carrier frequencies. In cases of this kind the carrier frequency must be chosen very high in order that the same will not be analyzed by (or act upon) the picture scanner means, and that no disturbing screens may arise in the incoming re-created picture. On the other hand, however, very high carrier frequencies are attended with serious drawbacks inasmuch as in the case of transmission over wire circuits (cables) these are usually not designed therefor, while in the case of radio transmission, there result inadmissibly wide side-bands.

Before describing the invention in detail, attention is directed to the drawing in which Fig. 1 shows one embodiment of the invention, and Fig. 2 shows a schematic diagram for illustrating the theory underlying the invention.

The invention discloses ways and means adapted to preclude the production of a disturbing screen impression in the incoming or re-created picture by the aid of comparatively low carrier frequencies. The basic principle of the invention shall be explained more fully by reference to a television receiver the essential parts of which are illustrated in Fig. 1. Referring to the latter, 1 denotes part of the Nipkow disk serving as a picture point distributor, 2 is the picture window, and 3 the glow discharge or gaseous conduction lamp to which the incoming currents are fed. 50 The "running coordinate" of the middle of the

scanning slit which, for instance, is constituted by a quadratic hole, shall be taken to be in the rectilinear line direction x , and the width of the scanner disk in its direction of motion shall be supposed to be f . If, then, the glow discharge lamp is fed with a sinuous alternating current potential of frequency s , the distribution of brightness along the picture line upon viewing through the Nipkow disk will be according to this relation:

$$H_x = \text{const.} \left[1 + \left(\frac{s}{\pi f} \sin \frac{\pi f}{s} \right)^2 \sin \frac{2\pi x}{s} \right]$$

(See Fritz Schröter, "Re-creation and amplification in televisors" Elektrische Nachrichtentechnik, 1929, vol. 6, page 445, Equation (4).) It can be seen from the formula that H_x throughout the length of the lines becomes constant no matter what the value of s , for which there holds true this equation:

$$s = f, f/2, f/3, \text{etc.}$$

Hence, if the auxiliary carrier frequency be chosen in accordance with this instruction and rule, then, in line with what is desired, the same will remain invisible in the re-created picture; and it is this fact in which the idea underlying this invention resides.

The production of the effect as here dealt with is illustrated also by graphic means (Fig. 2) which is based upon the case where $s=f$; in other words, during the shifting of the scanning slit by an amount equal to its own width, there occurs exactly a light and dark sequence of the receiver light source. In the figure the scanner slit in the receiver is shown in nine sequential positions differing each one-quarter period (numbers 1-9), the more or less marked darkening of the square slit being intended to indicate the luminous values resulting from the brightness curve shown on the left hand side and corresponding to each case. By integration of the brightness values in vertical direction it will be easy to understand that the sum total in visual observation according to the Talbot law or the exposure or blackening in photographic recording or impression in accordance to the law of additions, everywhere results in a constant "grey" which in the case here shown comprises one portion "white" and two portions "half-tone".

It can be easily seen that the principle hereinbefore disclosed for the selection of the carrier frequency will be successful in use and in a similar way in connection with picture telegraphs and television receivers of any desired kind of picture re-creation or re-assembly.

Having now described my invention, what I claim and desired to secure by Letters Patent is the following:

1. In a system of picture reception wherein the picture field is scanned by an aperture of elementary width and varying illumination, the method of excluding the effect on the picture of a constant frequency component of said varying illumination which comprises traversing the aperture across the field at a speed such that the aperture moves substantially the amount of its own width in an integral number of cycles of the said constant component.

2. In a system of picture reception wherein the picture field is scanned by an aperture of elementary width and varying illumination, the method of excluding the effect on the picture of a carrier frequency intermixed with the picture impulses which comprises varying the illumination of the aperture in accordance with the mixed frequencies, and traversing the aperture across the field at a speed such that the aperture moves by substantially the amount of its own width in an integral number of cycles of the carrier frequency. 5 10
